(57) CLAIM

The ornamental design for a ring holder, as shown and described.

DESCRIPTION

FIG. 1 is a left side perspective view of a ring holder showing my new design;

FIG. 2 is a right side perspective view thereof;

FIG. 3 is a front perspective view thereof;

FIG. 4 is a back perspective view thereof; and,

FIG. 5 is a top plan view thereof.

The ring holder has a pedestal, a base, and a holder.
